(57) CLAIM

The ornamental design for a flexible bottle handle, as shown.

DESCRIPTION

FIG. 1 is a front elevation of a flexible bottle handle showing my new design;

FIG. 2 is a front elevation thereof;

FIG. 3 is a left side elevation thereof;

FIG. 4 is a right side elevation thereof;

FIG. 5 is a top plan view thereof;

FIG. 6 is a bottom plan view thereof;

FIG. 7 is a right side isometric view thereof; and,

FIG. 8 is a left side isometric view thereof.

The bottle shown in broken lines in FIG. 1 is for illustrative purposes only and forms no part of the claimed design.
